UNITED STATES PATENT OFFICE.

JOHN FRANKLIN STACEY, OF NASHVILLE, TENNESSEE, ASSIGNOR OF ONE-HALF TO THOMAS E. MATTHEWS, OF NASHVILLE, TENNESSEE.

METHOD OF PRODUCING GAS.

SPECIFICATION forming part of Letters Patent No. 718,884, dated January 20, 1903.

Application filed January 4, 1902. Serial No. 88,427. (No model.)

To all whom it may concern:

Be it known that I, JOHN FRANKLIN STACEY, a citizen of the United States, residing at Nashville, in the county of Davidson, State of Tennessee, have invented certain new and useful Improvements in Methods of Producing Gas, of which the following is a description, reference being had to the accompanying drawings and to the figures of reference 10 marked thereon.

My invention relates to the art of manufacturing gas for heating and illuminating purposes from bituminous coal; and it consists in the hereinafter-described process by which 15 atmospheric air at a temperature of from 50° Fahrenheit in winter to 120° in summer (the temperature of the air being maintained considerably above the ordinary or normal by the heat radiated from the hot scrubber or 20 mixing-chamber, hereinafter referred to and illustrated by a drawing, said hot scrubber or mixing-chamber being located in a close room) is introduced into the gas produced by distillation of the coal in the ordinary and 25 well-known manner under such circumstances and conditions that the air and other substances produced by the distillation of the coal form a stable mixture, and the resulting gas, notwithstanding the increase in quantity 30 due to the volume of air introduced, not only burns with more complete combustion than would the unmixed gas, but the candle-power is maintained up to the standard now prevailing in the majority of large American 35 cities—to wit, up to from fifteen to sixteen candle-power. This result is attained by introducing the air directly into the stream of gas as it comes from the retorts before it has cooled below 200° to 205° Fahrenheit and before it has been freed from tar and other impurities. By introducing the air at this point 40 in the manufacture of the gas a greater proportion of air can be introduced than could be introduced at any other point in the process without reducing the candle-power below 45 the said prevailing standard, and at the same time a more complete and homogeneous resultant product is produced, burning without smoke and entirely satisfactory to consumers. I have found as the result of prac-

tical tests that a volume of air may be introduced at the temperature aforesaid and by the process aforesaid varying from six to nine per cent. of the output of the gasworks, the variation depending upon the quality of the 55 coal used—that is to say, of every one hundred cubic feet of gas manufactured by this process ninety-four to ninety-one per cent. will have been derived from the coal and the other six or nine per cent. from the air. I 60 have found also that by introducing air, as above described, the tendency to deposit naphthalene in the distributing-pipes is overcome and that the iron oxid used for purifying the gas is of much longer life than where 65 the gas is not mixed with air.

While it is to be understood that my process is not dependent upon the use of any particular form of apparatus, I have illustrated in the drawings a form of apparatus which I 70 prefer to use.

In the drawings, Figure 1 is a perspective view, partly broken away, showing a scrubber or mixer with suitable attachments for carrying out my improved process; and Fig. 2 75 shows a modified form of apparatus arranged to heat the air before its introduction into the stream of gas.

In the drawings, 1 is a hot scrubber or mixer, here shown as a rectangular box, but 80 which may be of any desired form. This box is provided with a series of perforated plates 2 and has at one end a gas-inlet 3, leading from the retorts and at the other end a gas-outlet 4, leading to the gasometer or to further devices for purifying the gas. The plates 2 are preferably so supported in the scrubber or mixer that a free space is left below, their lower edges extending from side to side of the box, and in operation this space is designed to be filled with the tar carried over by the gas from the retorts and caught in the passage of the gas through the scrubber or mixer by the perforated plates 2. To prevent the tar from rising too high in the box, overflow-outlets 5 are preferably provided at each 95 end of the box. The air-inlet tube 6 is connected directly to the gas-inlet 3, so that it delivers air into the stream of gas before it enters the scrubber or mixer or immediately upon its 100

entrance. The air-inlet tube is preferably provided with a cock 7, by which the amount of air introduced is regulated, and for the purpose of regulating the amount of air a meter 8 of ordinary construction is preferably connected with the tube 6.

It should be understood that at all times a partial vacuum is maintained in the scrubber or mixer by means of an exhauster. The vacuum at the outlet will ordinarily be maintained at about two and one-half inches water-column pressure, while the vacuum at the inlet end, by reason of the resistance of the plates 2 to the free passage of the gas, will not be more than one and one-half inches. It will usually be found desirable for the purpose of proper regulation to provide a pressure-indicator 9 near the inlet end.

In case it is desired to heat the air before its introduction into the gas a burner 10 may be arranged, as shown in Fig. 2, to heat the air-inlet tube 6 for such portion of its length, depending upon the size of the tube, as may be necessary to heat the air to the temperature desired.

The gas-inlet 3, as above stated, leads directly from the retorts. The gas which it carries should preferably be at a temperature of from 200° to 205° Fahrenheit, and as it comes directly from the retorts it is loaded to a greater or less extent with the tar or other impurities. The air introduced seems to combine with the tar and other impurities to form useful compounds, or at least to combine with the gas more readily by reason of the presence of the tar and other impurities, and the resulting mixture or combination after passing through the plates of the scrubber or mixer is a fixed gas of excellent quality, free from tendency to deposit naphthalene and not of materially less heating power than coal-gas unmixed with air and with a candle-power maintained up to the standard aforesaid.

Having thus described my invention, what

I claim, and desire to secure by Letters Patent, is—

1. In the manufacture of gas from coal, the process which consists in the introduction into the gas as it comes from the retorts and before it has cooled below 200° to 205° Fahrenheit, and before it has been freed from tar or other impurities, of atmospheric air, in the ratio or proportion of from six parts of air to ninety-four parts of gas derived from the coal, to nine parts of air to ninety-one parts of gas derived from the coal; the variation depending upon the quality of coal used, substantially as described.

2. In the manufacture of gas from coal the process which consists in the introduction into the gas as it comes from the retort and before it has cooled below 200° to 205° Fahrenheit, and before it has been freed from tar or other impurities, of atmospheric air in the ratio or proportion of from six parts of air to ninety-four parts of gas derived from the coal, to nine parts of air to ninety-one parts of gas derived from the coal, the mixture of gas and air being subjected to the action of a scrubber immediately upon the introduction of the air, substantially as described.

3. In the manufacture of gas from coal the process which consists in the introduction into the gas as it comes from the retort and before it has cooled below 200° to 205° Fahrenheit, and before it has been freed from tar or other impurities, of atmospheric air in the ratio or proportion of from six parts of air to ninety-four parts of gas derived from the coal, to nine parts of air to ninety-one parts of gas derived from the coal, the air being heated previous to its introduction into the gas, substantially as described.

In testimony whereof I affix my signature in presence of two witnesses.

JOHN FRANKLIN STACEY.
